DOCTOR MECHANISM FOR PAPER MACHINES

Ernst R. Ljungquist, Worcester, Mass., assignor to
 Lodding Engineering Corporation, Worcester,
 Mass., a corporation of Massachusetts

Application June 20, 1946, Serial No. 678,003

1 Claim. (Cl. 92—74)

1

The present invention relates to paper making machines, and more particularly to those devices known as doctors or scrapers which are employed for the purpose of cleaning the surfaces of paper making machine cylinder rolls.

The primary object of the present invention is to provide a cylinder roll doctor blade with simple, but yet highly efficient, means for moving said blade back and forth in a direction parallel to the axis of the calender roll being doctored.

A further object of the present invention is to provide a doctor blade vibrating mechanism of a character such that it may readily be attached to any of the usual type of calendering machines with little or no modifications required in either the calendering machine or in the vibrating mechanism.

With the above and other objectives in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings

Fig. 1 represents a vertical section of a calendering machine in which the present invention is embodied.

Fig. 2 represents a right side view of the calendering machine illustrated in Fig. 1.

Fig. 3 is a sectional view taken substantially along line 3—3 of Fig. 2.

Fig. 4 is a sectional view taken substantially along line 4—4 of Fig. 3.

Referring particularly to Figs. 1 and 2, the calendering machine therein disclosed comprises a machine base portion 10 having spaced frame members 11 and 12 projecting upwardly therefrom. Each of the frame members 11 and 12 have arms 13 and 14 projecting therefrom. Mounted on the calendering machine in the usual manner are calendering rolls designated generally by the numeral 15. A paper web 16 traverses the machine in a direction indicated by the arrows in Fig. 1, all in the usual manner.

Arranged substantially on opposite sides of the consecutive rolls 15 are doctor blades 17, each of which is suitably mounted in a blade holder 18. Each of these blade holders 18 comprises a substantially L-shaped member having welded, or otherwise suitably secured, to the opposite end portions thereof trunnion members in the

form of relatively short cylindrical shafts 19 and 20. Each of the oppositely opposed trunnion members 19 and 20, carried by the member 18, is rotatably journaled in a respective bracket member 21 and 22. As may be seen from Figs. 1 and 2, bracket members 21 and 22 are mounted in guide ways 23 and 24 respectively which are carried on the opposed calender arms 13 and 14. As may be understood from the above description, a turning movement of each holder 18 about its common pivotal axis, defined by the trunnions, serves to bring the blades 17 into engagement with the rotating surface of its associated calender roll 15.

15 A bolt 25 provides for the vertical adjustment of each of the bracket members 21 and 22 along the respective guide ways 23 and 24. Thus, each of the doctors 17 may be brought into proper adjustment with the rotating surface of its associated calender roll.

20 The present invention utilizes a motor drive mechanism in order to vibrate the doctor blades back and forth along the calender roll surface in a direction parallel to the axis of said roll.

25 Referring more specifically to Figs. 3 and 4, each of the bracket members 21 is provided with a vertical slot 26 for guiding a block 27 which is embraced therein. The lower portion of each of the blocks 27 is provided with rack teeth 28. In proper mesh with each rack is a pinion 29 carried by a stub-shaft 30 which is journaled in opposed side walls of the bracket member 21. Referring to Fig. 4, each trunnion shaft 19 is provided with a reduced portion 31 which is rotatably journaled within an aperture 32 provided in the block 27 and has provided in the distal end thereof a pin 33. The block 27 is thus embraced between the pin 33 and a shoulder portion 34 of the trunnion. As may be seen in Fig. 4, the bracket member 22 merely provides an aperture 34 into which a reduced end portion 35 of the trunnion is rotatably and slidably journaled. Thus, it may be understood that an oscillatory motion imparted to each pinion 29 will be effective to shift each doctor blade back and forth along its axis defined by the center line of its trunnions, which center line is disposed in parallelism with the centers of the rolls 15.

Provided on the outboard end of each of the stub-shafts 30 is either a single pulley 35 or a double pulley 36, depending on the particular location of the bracket member. Referring to Fig. 1, it may be seen that the top stub-shaft carried by arm 13 is connected to a mid stub-shaft by means of a belt or chain 37. The mid

stub-shaft is in turn similarly connected to a lower stub-shaft by means of a similar belt 38. Thus, the three stub-shafts disposed on the arm 13 are connected together so that they will be actuated in unison. The four stub-shafts carried by arm 14 are connected in a similar manner.

Provided on the base of the machine 10 is an electric motor 39, or other suitable driving means, which is connected by means of a belt 40 to a pulley 41. Pulley 41 is carried on the outboard end of a shaft 42 extending into a frame 43 therein to be connected to a counter shaft 44 by gears or other suitable means. The counter shaft 44, also journaled in the frame 43, carries a driving disk 45 on one end portion thereof. Eccentrically mounted upon the drive disk 45 is a pin 46 embraced by the upper end of a link member 47 whose lower end is pivotally connected to the free end of an oscillatory crank 48. This crank 48 is carried by and secured to a substantially horizontally disposed shaft 49 which is rockably journaled in spaced bearings 50 and 51 formed on the machine base 10. Also mounted upon the shaft 49 is a pulley 52 over which is trained a belt 53 which is also trained over the double pulley 36. A second pulley 53 is carried by the shaft 49 and is similarly connected to a double pulley 36 by means of a belt 54. Thus it may be understood that continuous rotation of the pulley 41 will be effective to oscillate the crank 48 thereby to impart an oscillatory endwise motion to each of the trunnions 19. Such oscillatory motions of each of the trunnions 19 will impart the desired back and forth or vibratory motions to each of the doctor blades 17. It will be obvious that the amplitude of vibratory motion imparted to the doctor blades 17 may readily be varied by merely changing the amount of eccentricity of the pin 46, the length of the crank 48, or by suitably altering the diameters of the pulleys 52 and 53.

From the above description it is to be understood that the present invention comprises a most novel type of doctoring actuating mechanism which, because of its inherent compactness, may be readily applied to most any type of calendering machine. Furthermore, the present invention comprises a doctor blade vibratory mechanism which, because of its simple but yet unique de-

sign, permits of inexpensive manufacture thereof.

I claim:

In a doctor operating mechanism for a paper making machine having spaced stationary frame members and a plurality of rolls stacked therebetween, a doctor blade disposed adjacent each of said rolls, a carrier for each of said doctor blades, trunnion members secured upon and extending beyond the opposite end portions of each of said carriers, means carried on said frame members for rotatably and slidably supporting one trunnion of each of said carriers, apertured block members each rotatably receiving therein a respective one of the other of said trunnion members, means to prevent relative endwise movement between each of said blocks and its associated trunnion member, and bracket members carried by said frame members for slidably supporting each of said blocks; the combination therewith of means for imparting back and forth endwise movements to said block carriers, said means comprising a rack mounted upon each of said blocks and disposed lengthwise of its associated carrier, a stub-shaft carried by each of said bracket members, each stub-shaft being disposed adjacent and substantially at right angles to its associated trunnion, a pinion carried upon each of said stub-shafts and meshing with a respective one of said racks, a pulley mounted upon each stub-shaft, a single motor-actuated crank member, and means connecting each of said pulleys with said crank member thereby to oscillate all of said doctor blades back and forth in unison.

ERNST R. LJUNGQUIST.
